CONSTRUCTION OF CYLINDRICAL PACKAGES

Filed Dec. 6, 1929

UNITED STATES PATENT OFFICE

WALTER VEIT, OF EAST ORANGE, NEW JERSEY, ASSIGNOR TO CONGOLEUM-NAIRN, INC.,
A CORPORATION OF NEW YORK

CONSTRUCTION OF CYLINDRICAL PACKAGES

Application filed December 6, 1929. Serial No. 412,113.

The present invention relates to packages and more particularly to improvements in the construction of cylindrical packages of the general class adapted for the transportation of rugs of felt base or linoleum, or a similar type of web material.

Packages of the general type referred to above, usually employ a core upon which the web material is rolled and subsequently wrapped. Such packages, because of their length, are usually transported, handled and stored on end, and accordingly are subjected to repeated and severe end-shocks which not infrequently seriously damage the edges of the packaged material at the opposite ends of the roll. To prevent such damage it has been proposed to extend the core beyond the edges of the web material wound thereon, with the idea in view that the extended core would receive and absorb the end-shocks. This has, however, not been successful because of end-wise shifting of the packaged material under normal conditions of handling, thereby bringing the edge of the web adjacent one or the other of the ends of the extended core where it is subjected to damage as before. It has also been proposed to pad the end of the rolled web with excelsior, burlap or the like, but such construction is very expensive.

My invention provides a novel type of package for shipping web material such as felt base or linoleum rugs, embodying a construction which eliminates the deficiencies of the types heretofore known. More particularly such construction comprises in combination, members projecting a substantial distance beyond each end of the rolled web and independent thereof which are adapted to receive and absorb all end-shocks, and means for positively preventing any substantial endwise shifting of the rolled web. These and other advantages will be fully apparent from the following descriptions and the accompanying drawing.

In the drawing:—

Figure I is a perspective view of the complete package constructed in accordance with my invention;

Figure II is a sectional view illustrating, in

detail, the novel type of end construction of the package;

Figure III is a sectional view illustrating, in detail, a slightly modified type of end construction.

Referring now to the drawing, numeral 1 indicates a core for the package, usually in the nature of a tube. Preferably, the core consists of a spirally wound chip-board tube of the conventional type, which will be slightly greater in length than the width of the web to be rolled thereon. Interfitting each open end of the tube 1, and united therewith is a shock-absorbing member 2 having a shoulder 4. This member is conveniently formed of wood and may be united with the tube by means of one or more nails 3. As clearly shown in the drawing the shock-absorbing members 2 project a substantial distance beyond the ends of the tube 1. Wherever the expression "substantial distance" is used throughout the specification and claim in defining the extent to which the shock-absorbing members project, it is intended to mean that the amount of such projection is approximately equal to or greater than one-half the difference between the diameter of the rolled web and the diameter of the member 2. Defining the expression in another manner, the amount of projection is such that a plane tangent to the periphery of the shock-absorbing member and the periphery of the end of the rolled web will form an angle of approximately 45° with the longitudinal axis of the package.

At each end of the tube is an annular flat ring 5, having an outside diameter approximately equal to the diameter of the rolled web to be packaged, and a central opening of such size as to fit over that portion of the shock-absorbing member 2 of smaller diameter and abut the shoulder 4 thereof. Preferably the central opening of the ring 5 is of such a dimension as to permit the ring to be located and positively clamped between the end of the tube 1 and the shoulder 4 of the shock-absorbing member. The annular ring 5 is formed of any suitable material such as chip-board or fibre board, having sufficient strength and rigidity to prevent shearing.

thereof by the shouldered member through endwise movement of the packaged material.

The web to be packaged, as for example a felt base rug α , is closely wound about the core or tube 1, intermediate the annular rings 5 at each end. The rolled web is then securely wrapped with heavy paper 6, the edge 7, of the paper being adhesively sealed.

To complete the package a cap 8, of 10 gummed paper or fabric is applied over the ends. In Figure II is shown a preferred form in which the end cap is provided with a central opening of the proper size to permit the cap to pass over and fit snugly about the 15 projecting member 2. According to this construction the cap engages the outer surface of the annular ring 5, and extends over the end of the outside wrapper 6, adhesively engaging both ring and wrapper and forming a 20 strong union therebetween. This construction presents an extremely neat appearance to the package, no paper or fabric extending over the shock-absorbing members to be torn, soiled or damaged in handling, etc. In Figure III is illustrated a modified construction 25 in which the end cap 8 covers the projecting shock-absorbing member as well as the annular ring 5, and extends over and adhesively engages the outside wrapper 6.

It will be apparent that the novel package 30 construction eliminates the defects of the packages heretofore known and provides a strong construction capable of withstanding any shock arising in the usual course of shipping and storing the package without damage to its contents. The annular rings being 35 securely retained against outward movement by the shouldered shock-absorbing members, positively prevent the contents of the package 40 from any substantial endwise movement. In addition, the rings provide a facing over the edges of the rolled web thereby giving additional protection against damage. The 45 shock-absorbing members, which are rigidly united with the core and positioned to extend a substantial distance beyond the end of the rolled web and the annular rings, serve to receive and absorb all end-shocks, thereby 50 protecting the contents of the package from damage normally caused by such shocks.

While I have described a preferred embodiment of my invention, certain modifications may be made without departing from the spirit thereof and I do not wish the scope of 55 the invention to be limited except as defined in the appended claim.

I claim:

An improved package for web material 60 comprising, in combination, a core upon which the web material may be wound; shouldered, shock-absorbing members interfitting and united with the respective ends of said core; annular rings at each end of said core, retained against outward movement by said 65 shouldered shock-absorbing members and

adapted to prevent any substantial endwise movement of the packaged web; a wrapper enclosing the packaged web; and a perforate end-cap overfitting each shock-absorbing member, enclosing the respective annular ring and extending over the edge of and engaging said wrapper; said shock-absorbing members being characterized by projecting beyond the end of the packaged web a distance such that a plane tangent to the periphery of the shock-absorbing member and the periphery of the end of the packaged web will form an angle of approximately 45° with the longitudinal axis of the package.

In testimony whereof, I affix my signature. 80
WALTER VEIT.
